HYDRAULIC WRENCH

William E. Stubbs, Berea, Ohio

Application June 10, 1946, Serial No. 675,785

8 Claims. (Cl. 81-129)

1

This invention relates to improvements in wrenches.

The primary object of this invention is the provision of an improved hydraulic wrench the parts of which are compactly assembled to admit of efficient adjustment of the jaws of the wrench through a simple handle adjustment at the end of the wrench.

Other objects and advantages of the invention will be apparent from the following detailed description.

In the accompanying drawing, forming a part of this specification, and wherein similar reference characters designate corresponding parts throughout the several views,

Figure 1 is a plan view of the wrench taken from the jaw side thereof.

Figure 2 is a cross sectional view taken longitudinally through the wrench.

Figure 3 is an end view of the wrench taken from the handle end.

Figure 4 is an enlarged cross sectional view taken substantially on the line 4-4 of Figure 2.

In the accompanying drawing, wherein for the purpose of illustration is shown only a preferred embodiment of the invention, the letter A may generally designate the wrench. It may include a supporting body or casing B having a fixed jaw C thereon. A movable jaw D is provided upon the body B connected to a plunger E operably disposed within the body B. A liquid is disposed within the body B and movable by means F to move the plunger back and forth and likewise move the jaw D with respect to the jaw C.

The body B is preferably of any approved material. According to the purpose for which the wrench is provided the length may vary, as will be well understood by those skilled in the art. The casing B includes a handle portion 10 within which a passageway 11 is provided. It extends substantially the full length of the body B. Beyond the handle 10 there is a lateral extension 12 upon the wrench within which is provided a plunger receiving passageway 13 therealong.

The passageway 11 in the handle is slightly larger in diameter than the passageway 11 at the jaw end of the wrench and at the juncture of these passageway portions there is a shoulder 15 adapted to receive a plunger washer 16. V-shaped packing rings 17 are cooperatively disposed in the passageway 11 with respect to the washer 16 and a second washer 18 is placed at the opposite end of the packing rings 17. A sleeve-like packing follower 20 is mounted in the

2

passageway 11 at the handle end 10 of the body, and this sleeve 20 at its extreme end is screw threaded at 21 for screw threading in the screw threaded end of the passageway 11. By threading the follower 20 the packing may be clamped against the shoulder 16 and upon the smooth portion of the piston adjusting rod 25 which extends along the passageway 11 and comprises part of the means F.

A sleeve-like piston 26 is threaded upon the screw portion 27 of the rod 25, and is movable in the passageway 11 between the packing above described and the jaw end of the casing or body. By turning the screw rod 25 the piston 26 may be moved along the passageway 11. At the extreme end of the passageway 11 a removable screw cap 30 is provided, having a socket 31 to receive a reduced step bearing 32 on the end of the screw rod 25, as shown in Figure 2. The handle portion 10 at its extreme end is externally screw threaded to receive a thrust collar or cap 40 which is flanged to receive a thrust washer 41 between the flange and the end of the handle 10. The screw rod 25 is reduced at its end 42 which extends through the thrust washer and the cap 40 and this portion 42 is externally screw threaded for threadably receiving a knob or wheel 44 retained thereon by a nut 45. Rotation of the wheel 44 will rotate the screw rod 25 and move the piston back and forth within the confines of the passageway 11 between the packing washer 16 and the step bearing cap 30.

The piston 26 may be provided with packing or piston rings 46 thereon, if so desired. To prevent rotation of the piston, since it must be fed along the rod or screw 25, I provide a ball or member 47 functioning as a key which slides along a groove 48 provided in the body B between the packing washer 16 and the cap 30.

In the chamber 13 of the extension portion 12 of the wrench body is located the slideable plunger E. This plunger E is of a desired length and it is provided with a key pin 50 which transversely extends at its ends beyond the sleeve 12 through slots 52 provided therein and keys the movable jaw D to the plunger for movement with the plunger. The length of the slots 52, will, of course, govern the degree of movement of the movable jaw with respect to the stationary jaw. The plunger E, if so desired, may be provided with packing rings to prevent leak of fluid from one side of the plunger to the other.

At the extreme jaw end of the casing B there is provided a duct 60 communicating the passage-

way 11 with the passageway 13. Similarly at the opposite end of the plunger passageway 13 there is provided a duct 62 which communicates the passageway 11 immediately at the far side of the packing washer 16 with the plunger chamber 13. The extension 12 at the extreme end of the body may be provided with a cap 65 which seals off the passageway 13. At the opposite end of the passageway 13 the extension 12 may be provided with a filler cap 67.

Any suitable liquid may be placed in the wrench. The passageway 11 and the chamber 13 at both sides of the piston 26 and the plunger E are filled with the liquid, preferably without air space.

It is quite obvious from the foregoing that in order to move the jaw D it is merely necessary to turn the wheel 44. This turns the rod 25 and feeds the piston 26 in the desired direction along the passageway 11. The liquid will pass through the ducts 60 and 62 and move the plunger E and the movable jaw D therewith in the desired direction.

It will be noted from Figures 1 and 3 that the jaws are tapered so as to permit their admission to places difficult of access.

Changes in details may be made to the form of invention herein shown and described without departing from the spirit of the invention or the scope of the following claims.

I claim:

1. In a hydraulic wrench the combination of a supporting body including a handle, a stationary jaw upon the supporting body, a movable jaw upon the supporting body, said supporting body having a pair of chambers therein with transverse ducts communicating the chambers at opposite ends thereof, a piston slidable in one of the chambers between said ducts, means for moving said piston along said chamber from exteriorly of the body, a plunger in the other chamber connected with the movable jaw for movement therewith, and a liquid in said chamber at opposite sides of the piston and plunger and movable through said ducts to move the jaw as the piston is moved along its chamber.

2. In a wrench structure the combination of an elongated supporting body having a liquid receiving passageway therealong, a stationary jaw upon said body, a movable jaw mounted upon the body for movement thereupon towards and away from said stationary jaw, a plunger slidable in said passageway and connected with said movable jaw, a liquid in said passageway at opposite sides of said plunger, and means for selectively pressing the liquid at either end of the plunger within said passageway for varying the position of the plunger and its movable jaw with respect to the stationary jaw.

3. In a wrench structure the combination of an elongated supporting body having a liquid receiving passageway therealong, a stationary jaw upon said body, a jaw movably mounted upon the body for movement thereupon towards and away from said stationary jaw, a plunger slidable in said passageway and fixedly connected with said movable jaw, a liquid in said passageway at opposite sides of the plunger, means for selectively pressuring moving the liquid at either end of the plunger within said passageway for varying the position of the plunger and its movable jaw with respect to the stationary jaw, said last mentioned means comprising a piston, and screw means mounted upon said body for adjusting the position of said piston.

4. In a hydraulic wrench the combination of

an elongated supporting body having a pair of compartments therein, duct means communicating said compartments at remote positions, a stationary jaw upon the body, a movable jaw upon the body, a plunger in one of the compartments between the duct means above mentioned, a slideable piston in the other compartments between the duct means above mentioned, a liquid in said compartments filling the ends thereof at opposite ends of the plunger and piston, and means for moving the piston for displacing the liquid and moving the plunger and the movable jaw therewith.

5. In a wrench structure the combination of a supporting body having chamber means therein, a stationary jaw upon the body, a movable jaw upon the body, a plunger connected with the movable jaw movable along the chamber means, a piston in the chamber means, a liquid in the chamber means at opposite ends of the plunger and piston, said body having duct means communicating the chamber means beyond similar ends of said piston and said plunger, and means for moving the piston for displacing the liquid and moving the plunger and the movable jaw therewith.

6. In a hydraulic wrench the combination of a supporting casing having a passageway therealong, a piston slideable in said passageway, means to prevent rotation of the piston, an elongated screw rotatably supported by the body supporting casing and threaded in the piston for moving the piston along the passageway upon rotation of the screw, a stationary jaw upon the casing, a movable jaw slideable along the casing, a liquid in the passageway at opposite sides of said piston, and means connected with the movable jaw and operable in said casing while being acted upon by the displacement of the liquid as an incident of movement of the piston, to move the movable jaw.

7. In a hydraulic wrench the combination of an elongated supporting body having a pair of substantially parallel compartments therealong, one of which is longer than the other, a stationary jaw mounted upon one end of said body, a movable jaw slidably mounted upon said body and encompassing both of said compartments, a plunger slideable in the shorter of said compartments fixedly connected with the movable jaw, a piston slideably movable along the longer compartment, said compartments having duct communication at opposite ends thereof and at opposite sides of the piston and plunger locations, a liquid in said compartments filling both ends thereof at opposite sides of the plunger and piston, a rotatable screw rod having screw threads thereon threadably engaging said piston for moving the piston along its compartment upon rotation of said rod, said rod being axially disposed in the longer of said compartments and having an operating head projecting at the end of the body opposite the stationary jaw.

8. In a hydraulic wrench structure the combination of an elongated casing having a pair of substantially parallel compartments therein, said casing at one end providing a handle and at its opposite end having a laterally extending stationary jaw, a movable jaw mounted upon said casing complementary to the stationary jaw, a plunger slideable in one of said compartments fixedly connected to the movable jaw for movement therewith, a piston slideable in the other compartment, liquid in both of said compartments at

the opposite ends of the piston and plunger, said compartments having communication with each other beyond both ends of the plunger and piston, and means mounted upon said casing for moving said piston and compressing the liquid for operating the plunger and the movable jaw therewith.
